UNITED STATES PATENT OFFICE.

MARK MELVILLE LEICHTER, OF SAN FRANCISCO, CALIFORNIA.

DESIGN FOR A BADGE OR EMBLEM.

43,052.

Specification for Design.

Patented Sept. 24, 1912.

Application filed February 6, 1911. Serial No. 607,006. Term of patent 7 years.

To all whom it may concern:

Be it known that I, MARK MELVILLE LEICHTER, a citizen of the United States, residing at San Francisco, in the county of San Francisco, State of California, have invented a new, original, and ornamental Design for a Badge or Emblem, of which the following is a specification, reference being had to the accompanying drawing, forming part thereof.

The figure is a plan view of a frying pan, showing to be embossed with my new design.

I claim:

The ornamental design for a badge or emblem, as shown.

MARK MELVILLE LEICHTER.

Witnesses:

SIDNEY N. COHEN,
WILLIAM KAUFMANN.
